UNITED STATES PATENT OFFICE

DORSEY F. ASBURY, OF BROOMES ISLAND, MARYLAND

RADIO APPARATUS

Application filed November 9, 1927. Serial No. 232,039.

My invention relates to radio apparatus and has particular reference to improvements in operating means for the movable parts of tuning units, such, for example, as 5 variable plate condensers, my object, generally speaking, being to provide an operating means of simple, inexpensive construction for adjusting a plurality of tuning units collectively and individually for the various 10 purposes set forth in my prior applications serially numbered 683,756; 689,338; 10,293; 72,514; 80,833; 89,443; 91,197; 95,138; 98,558; 108,174; 155,016; 166,516; reissue application 192,756, and in my Patents 1,598,415; 1,598, 15 441 and 1,608,804.

More particularly it is my purpose to provide an operating means including a single operator in the form of a knob which is rotatable and laterally movable and which, by 20 rotation, is effective to adjust the units collectively and, solely by lateral movement, is effective to adjust one or more of the units individually.

It also is my purpose, in connection with 25 an operator of the type mentioned, to provide means to indicate the correct adjustment of each of the units to establish a synchronized relation between them.

With the foregoing and other purposes in 30 view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Fig. 1 is a top plan view of a plural tuning unit radio apparatus showing my improved operating means for the units operatively connected with the latter;

Fig. 2, a central transverse section through the structure shown in Fig. 1;

Fig. 3, a section on the line 3—3 of Fig. 1;

Fig. 4, a front elevation, partly in section, of the structure shown in Fig. 1; and

Fig. 5, a rear elevation of a portion of the structure shown in Fig. 1.

Referring to the drawings in detail, it will

be observed that I have illustrated a radio apparatus embodying three tuning units *a*, *b* and *c* in the form of variable plate condensers which are duplicates of one another and each of which includes essentially two 55 sets of plates either set of which is adjustable with respect to the other set to change the tuning status of the unit. Specifically, each unit consists of a shaft 10 to which is adapted to be secured in any desired rotatably adjusted position with respect thereto, so as to rotate therewith a set of plates 12, while loose on said shaft so as to be rotatably adjustable with respect thereto is a U-shaped yoke or bracket 14 carrying a set of plates 16, the 60 two sets of plates 12, 16 as is apparent being arranged to be moved into different overlapping relations either by rotation of shaft 10 or by rotation of the yoke 14 with respect to said shaft.

The condensers *a*, *b*, *c* are arranged preferably, but not necessarily in triangular relation in a common horizontal plane and with their shafts 10 parallel to one another, that is, condensers *a*, *c* are arranged abreast while condenser *b* is located behind condensers *a*, *c* with its shaft 10 midway between the shafts 10 of condensers *a*, *c*, said condensers being supported in this relation by suitable supports 18 in which the respective shafts 10 65 are rotatably mounted.

The shafts 10 of the respective condensers are connected together for collective rotation by any suitable or desired form of gearing, for example, as shown, by means of pulleys 20 fixed to said shafts and belts 22 trained over said pulleys.

An operator shaft 24 has a suitable universal joint connection 26 at its inner end with the shaft 10 of condenser *b* whereby rotation of said operator shaft is effective through the pulleys 20 and belts 22 to rotate the respective shafts 10 collectively and whereby said operator shaft is swingable laterally to rotatably adjust the yokes 14 of condensers *a*, *c* individually thereby to adjust the plates 16 of said condensers individually in a manner which will presently appear.

Operator shaft 24 extends through an 100

opening in a panel board 28 located in front of the condensers *a*, *b*, *c* and is equipped at its outer end with a knob 30 whereby it may conveniently be rotated and moved laterally, 5 while inwardly of said panel board said shaft has engaged therewith the slotted free end portions of a pair of lever arms 32, 34 the former of which is fixed to the yoke 14 of condenser *c* and the latter of which is pivoted as at 36 to a suitable fixed part of the apparatus and is connected to the yoke 14 of condenser *a* by a link 38, lever arm 32 being disposed substantially horizontally and lever arm 34 being disposed substantially vertically 15 whereby vertical swinging movement of said operator shaft is effective to swing lever arm 32 to rotate the yoke 14 of condenser *c* without swinging lever arm 34 and whereby horizontal swinging movement of 20 said operator shaft is effective to swing lever arm 34 to rotate the yoke of condenser *a* without swinging lever arm 32.

On the shaft 10 of one of the condensers, condenser *a* in this instance, is fixed a dial 40 and arranged for movement across the face of this dial is the free end portion of a substantially horizontally disposed indicator arm 42 which is pivoted at its other end as at 44 to a suitable fixed part of the apparatus such as panel board 28, said arm being provided intermediately with a longitudinal slot 46 in which operates a pin 48 carried by an arm 50 which is pivoted at one end to the operator shaft 24 and at its other end is slidably, pivotally engaged with a friction device 52, the result being that horizontal swinging movement of the operator shaft is ineffective, because of the pin and slot connection 46, 48 between the arm 50 and the 35 indicator arm 42, to move said indicator arm, while vertical swinging movement of the operator shaft is effective to swing the free end portion of the indicator arm vertically across the face of said dial 40, the friction device 52 40 serving to hold the operator shaft and the indicator arm in any vertically adjusted position to which they may be moved.

A second substantially horizontally disposed indicator arm 54 is pivotally connected 50 at one end to the operator shaft 24 and also extends across the face of dial 40, being slidably pivotally engaged at its other end with a friction device 56 which operates through said arm to hold the operator shaft in any 55 horizontally adjusted position to which it may be moved.

On the indicator arm 42 is a pointer 58 while on the indicator arm 54 is a pointer 60, said pointers being adapted for cooperation 60 with suitable indices on the dial 40 to indicate the correct position of the knob 30 to establish a synchronized relation between the tuning units for any given wave length.

The yoke 14 of unit *b* is not connected with 65 the operator shaft 24 for rotation by the lat-

ter, but it has secured thereto an arm 62 equipped with a knob 64 and a pin 66 adapted to be engaged in a recess 68 in one of the supports 18 to hold said yoke against rotation. To adjust the yoke 14 and the plates 70 16 of condenser *b*, the arm 62 is flexed outward to disengage the pin 66 from the recess 68 and said arm then is swung either up or down to swing the yoke 14 and thus either increase or decrease the amount of overlap 75 between the plates 12, 16.

In the use of my improved operating mechanism the dial 40 is loosened from shaft 10 of condenser *a* and the plates 12 of each unit are loosened from their respective shafts 10 80 and rotated to a mean position. Each yoke 14 with its plates 16 also is rotated to a mean position. Each unit then is tuned individually by rotatable adjustment of the plates 12 to a mean wave length. Knob 30 then is rotated and swung to a mean position and the plates 12 then are tightened to their respective shafts 10, so as thereafter to rotate with said shafts. Dial 40 next is rotated to a mean position on its shaft and tightened thereto. 90 The positions of pointers 58, 60 then are marked by dots on the face of dial 40. Knob 30 then is rotated to adjust the plates 12 collectively until another wave length is encountered, when condenser *b* is adjusted by 95 the knob 30 to exact tune with such wave when arm 62 is in its mean position, said arm affording means to determine by swinging it first in one direction and then in the other when the condenser *b* is in exact tune with 100 any given wave length when said arm is in a mean position. Next, knob 30 is moved up and down to oscillate the plates 16 of unit *c* to bring this unit into exact tune with the same wave length, the position of pointer 58 105 when this has been accomplished being marked by a dot on the face of dial 40. Knob 30 then is moved back and forth in a horizontal plane to oscillate the plates 16 of unit *a* to bring this unit into exact tune with the 110 same wave length and when this has been accomplished the position of pointer 60 is marked by a dot on the face of dial 40. In this way the units are tuned collectively and 115 individually to each of a number of different wave lengths and the dots of each of the two series resulting from marking the different positions of the pointers 58, 60 preferably but not necessarily then are joined together as indicated by the lines 70, 72, respectively, 120 so that whenever, subsequently, it is desired to tune all of the units accurately with any desired wave length all that is necessary to be done is to rotate the knob 30 to adjust the plates 12 of the units collectively until the desired wave length is encountered, which may be determined by bringing a given division mark 74 on the marginal portion of the dial 40 into alignment with the outer edge of 125 arm 42, then move the knob up or down as 130

- may be required to bring pointer 58 into registry with the line 70, which indicates the correct adjustment of plates 16 of unit *c* to synchronize this unit with unit *b*, and 5 finally move the knob back or forth as may be required to bring pointer 60 into registry with the line 72, which indicates the correct adjustment of the plates 16 of unit *a* to synchronize this unit with units *b* and *c*. Thus, 10 once the lines 70, 72 have been marked on the dial 40 it is a relatively simple matter, when the different rotated positions of the dial for tuning the units with different wave lengths are known, to adjust the units collectively 15 by rotation of the knob 30 to approximate tune with a selected wave length and then bring the units accurately into tune with that wave length by moving the knob either up or down and back or forth horizontally.
- 20 From the foregoing description considered in connection with the accompanying drawings it is believed that the construction, operation and advantages of my improved operating means will be clearly understood. I 25 desire to point out, however, that various changes and desirable additions may be made in and to the structure illustrated within the spirit and scope of my invention as defined in the appended claims.
- 30 I claim:
1. In radio apparatus, a condenser embodying two sets of blades only, each set being individually adjustable, a single operator, and connections between the operator and each set of blades responsive respectively to different movements of the operator to individually adjust said sets.
  2. In radio apparatus, a condenser embodying two sets of blades only, each set being individually adjustable, a single operator, connections between the operator and each set of blades responsive respectively to different movements of the operator to individually adjust said sets, an indicating 45 member responsive to individual adjustment of one of said sets, and a second indicating member responsive to individual adjustment of another of said sets.
  3. In radio apparatus, a pair of adjustable 50 condensers, an operator rotatable and laterally movable, means whereby rotation of said operator is effective to adjust said condensers collectively, and means independent of said first named means whereby lateral movement 55 of said operator is effective to adjust one of said condensers individually.
  4. In radio apparatus, a pair of condensers each including two individually adjustable elements, a single operator, means whereby 60 said operator is movable to adjust one of the elements of each condenser collectively, and means whereby said operator is movable to adjust the other element of each condenser individually.
  5. In radio apparatus, a pair of condensers
- each including two individually adjustable elements, a single operator rotatable and laterally movable, means whereby rotation of said operator is effective to adjust one of the elements of each condenser collectively, and 70 means whereby lateral movement of said operator is effective to adjust the other element of each condenser individually.
6. In radio apparatus, a tuning unit including two individually adjustable tuning elements, a single operator rotatable and laterally movable, and connections between said operator and said tuning elements whereby rotation of said operator is effective to adjust one of said elements individually and 75 whereby lateral movement of said operator is effective to adjust the other of said elements individually.
7. In radio apparatus, a plurality of condensers each including an adjustable element and at least one of which includes a second adjustable element, a single operator, a collective drive connection between said operator and an adjustable element of each condenser, and means whereby said operator is 80 movable to individually adjust the second element of said last mentioned condenser.
8. In radio apparatus, a plurality of variable condensers, one of which includes two 85 movably adjustable sections and each of the remainder at least one movably adjustable section, each of said sections being formed of a plurality of blades adapted to interdigitate with the blades of the other section of the condenser of which it forms a part, an operating knob connected with movably adjustable sections of all the condensers to collectively 90 vary the extent of interdigitation between the blades of all related sections, and means operable by said knob to movably adjust the other section of the condenser having two 95 movably adjustable sections to vary the extent of interdigitation between the blades of the sections of the last named condenser independently of the adjustment of a section 100 forming a part of any other condenser.
- 105 In testimony whereof I hereunto affix my signature.
